UNITED STATES PATENT OFFICE.

HENRY SOULEN, OF MILWAUKEE, WISCONSIN.

TRACK AND HANGER FOR SLIDING DOORS.

SPECIFICATION forming part of Letters Patent No. 349,536, dated September 21, 1886.

Application filed March 23, 1886. Serial No. 196,281. (No model.)

To all whom it may concern:

Be it known that I, HENRY SOULEN, a citizen of the United States, of Milwaukee, in the county of Milwaukee and State of Wisconsin, 5 have invented certain new and useful Improvements in Tracks and Hangers for Sliding Doors; and I do hereby declare that the following is a full, clear, and exact description of the invention, which will enable others skilled in 10 the art to which it pertains to make and use the same, reference being had to the accompanying drawings, and to the letters of reference marked thereon, which form a part of this specification.

15 The objects of my invention are, first, to maintain a perfect joint between the doors when they are closed; second, to maintain the edges of the doors, when they are open and withdrawn into the pockets in the wall, flush 20 or parallel with the sides of the door frame or jambs; and, third, to prevent the binding of the doors and facilitate their movement.

It consists, essentially, of means for adjusting the track vertically at one or more points, 25 of suspending the track so as to cause it to conform laterally to the travel of the doors and the hanger-wheels, and of anti-friction hangers adapted for use with said adjustable track.

In the accompanying drawings, like letters 30 refer to the same parts in the several figures.

Figure 1 is a longitudinal vertical section of my improved track, showing a pair of sliding doors, one of which is provided with my improved hangers, the lath and plastering being 35 removed. Fig. 2 is a plan view of the casting by which my hanger is attached to the door. Fig. 3 is a transverse vertical section, on an enlarged scale, on the line $z z$, Fig. 1, of the track and adjusting-wedges employed at one 40 end of said box. Fig. 4 is an end elevation of said wedges, and of the adjusting-bolt used therewith. Fig. 5 is a cross-section of one of the hangers, the track, and the parts associated therewith; and Fig. 6 is a partial longitudinal 45 section of the hanger on the line $x x$, Fig. 5.

It is a well-known fact that sliding doors and the tracks upon which they run, generally, if not always, get out of adjustment, owing to the settling of the building, the distortion of its 50 walls, and the warping of the tracks and the parts to which they are attached, as well as of

the doors and casings themselves. To meet these unavoidable defects and the difficulties arising therefrom, various adjustable hangers have been devised, by which the doors (when used in pairs) may be adjusted to form a perfect joint between their contiguous edges, or to bring their inner edges flush or parallel with the sides of the door frame or jambs when they are opened or withdrawn into the pockets in 60 the wall or partition. It will be seen, however, that when the track is rigidly secured in place adjustable hangers cannot remedy all the defects resulting from the warping or deflection of said track. The edges of the doors 65 may be made to meet and form a perfect joint at the center of the opening; but if the track is out of alignment their inner edges will not be flush or parallel with the jambs when the doors are withdrawn into the pockets. When 70 the track is thus rigidly secured to the wall, any lateral warping or deflection will cause the doors or hangers to bind, and thus obstruct their movement—imperfections which it is obvious the adjustable hangers cannot correct, 75 and which, with the defects previously mentioned, it is the design of my improvements to effectually remedy.

Referring to the accompanying drawings, A is a box composed of top and sides, to 80 the inner faces of which are attached, at their lower edges, parallel and equidistant from each other, the rails $a a$, which are preferably made of maple or some similar wood, and, together with said box, constitute the track. The top 85 is securely screwed to the sides, which are in turn screwed to pieces which close the ends of the box and prevent said sides from warping or spreading. The box A is suspended at one end and at intermediate points by bolts $b b$, 90 which pass up through the top thereof along its longitudinal center and engage at their threaded ends with nuts $b' b'$, embedded along the longitudinal center of the head-piece B, which is secured in a horizontal position between the studding N N, as seen in Fig. 5. The bolts $b b$ are secured in the top of box A by pins and washers $g g$, as shown in Figs. 5 and 6, which permit them to be turned therein. The holes in the head-piece B, through 95 which the bolts b pass, are made a little larger than said bolts, and the studs N N are cut

away adjacent to the sides of said box A, to permit of a slight lateral movement of the latter, whereby the rails *a a* adjust themselves readily to any irregularity in the line of travel 5 of the hanger-wheels, and the doors and hangers are prevented from binding against the parts adjacent thereto.

To the under side of the box A, at the end opposite that supported by a bolt, *b*, I attach a wedge, *F*, which rests upon a wedge, *G*, supported in turn by a cross-piece, *H*, fastened to studs *N N*. The support *H* is grooved to receive a tongue formed on wedge *G*, and thereby retain said wedge in place. A 15 bolt, *c*, provided near the head with a shoulder, *c'*, by which it is secured with its head flush with the face of the plaster, passes at its threaded end into the end of the wedge *G*, and engages with a nut embedded therein, as shown 20 in Fig. 3. The head and shoulder *c'* of said bolt *c* are inclosed and bear in a sleeve, *I*, which is formed in two sections, as shown by dotted lines, Fig. 4, to permit the insertion of shoulder *c'*, and attached to a board, 25 *L*, fastened to the studding underneath the lath, as shown in Fig. 3.

I prefer, in connection with my hanger, to suspend the track at three points above the door-opening by bolts *b b*, one located at the 30 center and one at or near each side, as seen in Fig. 1, so as to be accessible for the purpose of adjustment through the narrow opening formed in the frame or head jamb to receive the upper ends of the doors, and between the 35 rails *a a*. To render the track slightly flexible vertically, the box A is cut transversely at *s s* through the top and sides down to the top of rails *a a*, near the bolts *b b* at the sides of the door-opening, Fig. 1. To prevent the 40 distortion or warping of the box where the cuts *s s* are made, I secure in the end of each section of the top made by said cuts dowel-pins *i i*, which project into the end of the adjacent section. The adjustment of the track 45 required at the center of the doorway is so slight that it is not necessary to cut the box at that point.

When adjustable hangers are used, the bolt *b* at the center of the doorway may be dispensed with, since the doors may be adjusted 50 by means of said hangers to form a perfect joint between their edges at that point.

With my adjustable track adjustable hangers may be dispensed with, and the non-adjustable hangers *D D* employed to better advantage, not only because they are cheaper, but also because they run smoother, and are less liable to rattle.

The hanger-frames *P* are preferably made 60 U-shaped, and are provided at their bases with wedge-shaped dovetail tenons, which are inserted into and engage with similar grooves formed in base-plates *ee*, attached to the doors, as seen in Figs. 5 and 6. The upright limbs 65 of said hanger-frames *P* are mortised to receive the ends of the steel bars *n*, which are

notched on their lower edges and secured in place by set-screws *o o*, as shown in Figs. 5 and 6.

The hanger frames and bars *n* may be made 70 entirely of iron and cast together in a single piece, although I prefer the construction first described, as being the better and more economical way of forming the bearings traversed by the axles of the hanger-wheels *T T*, which 75 are secured, in the usual manner, in pairs upon the short axles *ll*, as shown in Fig. 5.

To reduce the friction of the wheels *T* upon the rails *a a*, I form the rims of said wheels without flanges, and provide each hanger with 80 a wooden friction-ball, *d*, mounted between the rails *a a*, upon a vertical pin rising from the center of the frame *P*, so as to bear on either side against said rails *a a*, and thereby 85 to retain the hanger and its wheels *T T* in their proper positions relative to the track and prevent the doors from binding against the jambs or stops.

When the track is placed in position, it is 90 permanently adjusted at one end (that opposite the wedges) and set in as perfect alignment as practicable. After the doors are hung and the walls finished the track can be readily adjusted, whenever it becomes necessary, 95 by turning the adjusting-bolts *b b* and *c* in or out, as required, with an ordinary screw-driver. In practice the alignment of the track is accomplished by first adjusting the bolt *b* at the side of the door adjacent to the fixed end of said track, so as to bring the exposed 100 edge of the door on that side flush with the jamb when the door is in the pocket. The bolts *b b* at the opposite side and center are then adjusted to bring the approaching edges of the doors together at the center, so as to 105 form a perfect joint, the center bolt *b* correcting any vertical deflection of the track between the bolts *b b* at the sides of the door-opening. Finally, the screw *c* is turned in or out, as required, to bring the inner edge of the 110 adjacent door, when it is opened, flush with the jamb on that side.

The details of my improvements may be 115 variously modified without departure from the spirit of my invention. With very slight change they are equally applicable to single sliding doors. The wedges *F* and *G* may be turned at right angles to the position in which they are shown in the drawings, and the screw *c* made to project through the door frame or 120 jamb; or the wedges may be dispensed with altogether and a bolt, like those shown at *b b*, used in their place, with some device connected therewith—such as a worm and pinion—for adjusting it from the outside.

Collars like that shown in connection with 125 bolt *c* may be used with the several bolts *b b*, instead of the pins and washers *g g*.

I claim—

1. The combination, with a sliding door and hanger, of the track adjustably suspended from above, and adjusting-bolts *b b*, accessible 130

through the opening traversed by said hanger and the upper edge of said door, substantially as and for the purposes set forth.

2. The combination, with a sliding door and hanger, of the box A, open at the bottom and adjustably suspended at the top, rails *a a*, attached to the inside of said box, and adjusting-bolts *b b*, accessible through the opening traversed by said hanger and the upper edge 10 of said door, substantially as and for the purposes set forth.

3. The combination, with a sliding door and its hangers, of the track supported at intervals by adjusting-bolts *b b*, and at one end by 15 adjusting-wedge G, substantially as and for the purposes set forth.

4. The combination, with a sliding door and its hangers, of the track supported at one end by wedges F and G, and adjusting-screw *c*, substantially as and for the purposes set forth.

5. The combination, with a sliding door and hanger, of the box A, open at the bottom and having transverse cut *s* through the top and sides, rails *a a*, secured to the inside of said 25 box, head-piece B, provided with nuts *b' b'*, and adjusting-bolts *b b*, by which said box is suspended from said head-piece, and which are accessible through the opening traversed by said hanger and the upper edge of said 30 door, substantially as and for the purposes set forth.

6. The combination, with a sliding door and hanger, of the track centrally suspended from above and movable laterally, substantially as and for the purposes set forth.

7. The combination, with a sliding door and hanger, of the box A, open at the bottom, centrally suspended from above, and capable of lateral movement, rails *a a*, secured to the inside of said box, and adjusting-bolts *b b*, by 40 which said box is suspended, substantially as and for the purposes set forth.

8. The combination, with a sliding door, of the vertically-adjustable track, hanger D, composed of the wheels or sheaves TT, and frame 45 P, provided with the bearing-bar *n*, and a wedge-shaped dovetail tenon, and the attachment-plate *e*, having a similarly-shaped groove to receive said tenon, whereby said hanger is hung upon said track and rigidly secured to 50 said door, substantially as and for the purposes set forth.

In testimony that I claim the foregoing as my own I affix my signature in presence of two witnesses.

HENRY SOULEN.
